UNITED STATES PATENT OFFICE.

HUGO KLAGSBRUNN, OF MOUNT VERNON, NEW YORK.

DOLL-HEAD.

1,135,292.

Specification of Letters Patent.

Patented Apr. 13, 1915.

Application filed November 14, 1914. Serial No. 872,148.

To all whom it may concern:

Be it known that I, HUGO KLAGSBRUNN, a subject of the Emperor of Austria, residing at Mount Vernon, in the county of West- 5 chester and State of New York, have invented new and useful Improvements in Doll-Heads, of which the following is a specification.

My invention relates to doll heads and has 10 as its principal object to provide a device whereby dolls' heads may be made with eyes adapted to turn both up and down and to either side, so as to produce the effect of open and closed eyes and of eyes looking 15 straight forward or sidewise, respectively.

A further object of my invention is to provide a device of this character which is simple in construction, infallible of operation and cheap in manufacture.

20 A final object of my invention is to provide such a device which may be mounted in place easily and quickly.

I attain my objects by providing a mechanism hereinafter more specifically described and illustrated in the accompanying drawing in which:

Figure 1 is a perspective view of a doll's head provided with my device, with sidewise looking eyes. Fig. 2 is a front elevation of my device as applied to the inside of the front part of a doll's head, fractionally shown. Fig. 3 is a vertical section of Fig. 2 taken on the line 3—3 thereof. Fig. 4 is an elevational detail view showing an alternate form of one part of my device. Fig. 25 5 is a perspective detail view of a part.

The same part is designated by the same reference character throughout the several views.

40 Referring more particularly to the drawing, 10 is a bearing made either of the same material as the doll's head and integral therewith, or separately of a piece of wood or the like, glued to the inside of the doll's head 11, in about the position corresponding to the nose of the doll, between the eye holes 12, said bearing 10 being open at the front and adapted to be closed by a covering plate 13 glued on after inserting in the bearing 10 45 a cranked shaft 14 rotatably mounted therein. The cranked shaft 14 carries, rotatably on either vertical end 15 thereof, a pair of globes 16 representing eye-balls which register with the eyeholes 12 and have pupils and 50 iris painted or otherwise applied to the parts which normally, in the erect position

of the doll, appear within the eye holes 12. At the side opposite to this part of the globes 16, below the horizontal center line thereof, I provide rods 18 rigidly attached, 60 preferably screwed into the globes 16, each rod 18 having an eyelet 19 at its end and the two rods 18 connected to each other by a horizontal link 20 hooked, at either end thereof, into the said eyelets 19 and carrying, attached to it, a weight 21. On top of each globe 16 I provide a washer 22 on the shaft ends 15 which latter, after the washers 22 are in place, have to be pressed with a pair of pliers, producing the corrugations 23 65 to prevent the slipping off of the washers and the globes 16.

When the doll is laid on its back, the weight 21 draws the globes 16 down and thereby causes the shaft 14 to turn in its 70 horizontal bearing, the turning movement being limited by one shaft-end 15 which is prolonged for the purpose, butting against the inside of the forehead part 26 of the doll. By this movement the part of the globes 16 75 above the pupils appears in the eyeholes 12, which part is painted so as to represent closed eye-lids and thus produces the effect of eyes closed as in sleep. When the doll is, thereafter, raised to its original, erect 80 position, the weight causes the shaft 14 to turn back again to its former, normal position, thus producing the effect of the doll's opening its eyes. This movement is limited by the lower horizontal parts 24 of the 85 cranked shaft 14 butting against the inside 90 of the doll's head.

The sideward movement of the eyes is produced by the action of the same weight 21 when the doll is laid on one side, the 95 globes 16 being then turned around their vertical axis 15 by means of the rods 18 on which the weight 21 acts. This movement is limited, on either side, by the respective end of the connecting link 20 butting against 100 the inside of the cheek-parts 26 of the doll's head but, if the length of the link 20 is insufficient for that purpose, prolongations 27 thereof, as in Fig. 4, may be provided.

When the bearing 10 is integral with the 105 doll's head, I introduce the remainder of the mechanism, otherwise complete, through the neck-opening of the doll's head by means of a pair of tongs and place the shaft 14 into position in the bearing, thereafter introducing, in the same way, the covering plate 13 110 previously provided with glue and paste it

on to the front of the bearing 10, thereby closing it. The wedge shaped lower end of the covering plate 13 and the corresponding recess 28 in the bearing are provided for 5 the purpose of easily locating the right position in which the covering plate 13 has to be fixed.

When the bearing 10 is a separate piece, as in the accompanying drawing, I assemble 10 the whole device as shown before introducing it into the doll's head in the above mentioned manner and pasting it in position with some convenient composition. The 15 sides of the bearing 10 coacting with the downwardly bent parts of the shaft 14 provide a suitable guide for the latter, preventing lateral deviations or oscillations thereof.

While I have thus described and shown the preferred form of my invention, it is understood that I do not want to be limited 20 by its mechanical details and may resort to such alterations and modifications as come within the scope of the claims hereunto appended.

25 I claim:

1. A mechanism for dolls' eyes comprising, in combination, a bearing at the inside of a doll's head, a cranked shaft having a central, horizontal part rotatably carried by

said bearing, and two vertical ends each carrying, rotatably thereon, a globe representing an eyeball and provided with pupils and iris at their part normally appearing in the eyeholes of said doll's head, and weight-controlled means for turning said eyes in respect to said eyeholes so as to produce the effect of open or closed eyes and of eyes looking straight forward or sidewise, respectively, substantially as set forth. 30 35

2. A mechanism for dolls' eyes comprising, in combination, a bearing at the inside of a doll's head, a cranked shaft having a central, horizontal part rotatably mounted in said bearing and two vertical ends carrying, rotatably thereon, a pair of globes representing eyeballs and provided with pupils and iris at their part normally appearing in the eyeholes of said doll's head, weight controlled means for turning said eyeballs in respect to said eye-holes and means for limiting said turning movement in both directions to the required extent, substantially as 40 45 50 and for the purpose set forth.

HUGO KLAGSBRUNN.
